GOLF TEE

J. Henry Walsh, Cranston, R. I.

Application August 1, 1956, Serial No. 42,475

Term of patent 14 years

(Cl. D34—5)

I claim:

The ornamental design for a golf tee, as shown.
